UNITED STATES PATENT OFFICE.

JOHN T. HORTON, OF BROOKLYN, NEW YORK.

HOISTING MECHANISM.

Application filed November 2, 1923. Serial No. 672,328.

To all whom it may concern:

Be it known that I, JOHN T. HORTON, a citizen of the United States, and a resident of New York, borough of Brooklyn, in the 5 county of Kings and State of New York, have invented certain new and useful Improvements in Hoisting Mechanisms, of which the following is a specification.

This invention relates to hoisting mechanisms, and has for its object to provide a mechanism of the class specified, simple in control and efficient in operation. Other features of improvement will appear later herein.

15 With these ends in view my improvements comprise features illustrated in their preferred embodiment in the drawings accompanying this specification, wherein:—

Figure 1 is a side elevation of my improved mechanism. Fig. 2 is a front elevation looking from the left of Fig. 1. Fig. 3 is a fragmentary sectional view on line 3—3 of Fig. 1. All the figures of the drawing are to one scale.

25 The mechanism is directed to the operation and control of two winding drums 2, 4 and is preferably carried by two upright members 5, 6, such as steel channels. Said drums may be connected by cables, wound 30 about said drums, to any desired type of hoisting apparatus, such for instance as a boom derrick. In this case the cable from one drum would be attached to said boom for raising and lowering thereof and the 35 other cable would be rove through the free end of the boom, terminating in a hook or the like, for hoisting. Such types of boom derrick are well known and the details thereof are omitted herein as not pertinent

40 to the present invention. Channels 5, 6 may be tied together by cross members 7, 8, 9 and 10, respectively, and electric driving motor 11 may be mounted on cross members 9, 10 near the base of the mechanism. Said 45 motor 11 preferably has two pinions 12, 13 fixed to its shaft 14. Said pinions are of different sizes and are adapted for engagement, one at a time, with gears 15, 16, respectively, fixed to sleeve 17 slidably 50 mounted on intermediate shaft 18. Rotary motion is transmitted from either of gears 15, 16 to shaft 18 through key 19. By this well known arrangement either of two speeds may be transmitted to shaft 18 from 55 a constant speed of motor 11.

Gears 15, 16 may be shifted along shaft 18 into engagement with their respective pinions 12, 13 by means of lever 27 pivoted to a bracket fixed to cross member 9. Said lever 27 has yoke 28 thereof in engagement with and between flanges 29, 30 of sleeve 17. Shaft 18 and other shafts which will presently be described have their bearings in opposite skeleton frames 20, 21 bolted to uprights 5, 6, respectively. Pinion 22 is 60 fixed to shaft 18 outboard frame 20, and meshes with gear 23 fixed to control-shaft 24. Turning freely on said control-shaft and near opposite ends thereof, within frames 20, 21, are pinions 25, 26. Pinion 25 65 meshes with large gear 31 fixed to drum 4, and pinion 26 meshes with large gear 32 fixed to drum 2. Control-shaft 24, and drum shafts 33, 34 have their bearings in said frames 20, 21. Inwardly facing from pinions 25, 26 and integral therewith, respectively, are dished friction members 35, 36 for engagement with opposite male friction members 37, 38, respectively. Said male members 37, 38 are mounted coaxially with 70 members 35, 36 on control-shaft 24 and are 75 slidable lengthwise said shaft but are constrained to rotate therewith by keys 39, 40, respectively.

Fixed to cross member 8 and encircling 80 shaft 24, midway between frames 20, 21, is center bearing 41. Said bearing has opposite cams or wedges 42, 43 for engagement with complementary cams 44, 45, respectively, mounted for rotation and endwise movement on said shaft 24. Said cams 44, 45 are provided with arms 46, 47, respectively, whereby said cams may be rotated through a small arc in engagement with their respective cam faces of bearing 41 for thrusting 85 male friction members 37, 38 into engagement with their respective dished friction members 35, 36 of pinions 25, 26 for transmitting rotary motion from shaft 24 to said 90 pinions.

100 Cam 44 may be oscillated by means of lever 48 fixed to shaft 49 having bearings in frame 21 and brackets 54, 55 by the following means: Said shaft 49 has arm 50 fixed thereto and the free end of said arm is connected with the free end of cam arm 46 by links 51, 51, so that, when lever 48 is pulled to the left, Fig. 1, cam 44 is rotated in clockwise direction whereby friction member 37 is forced to the left, Figs. 2 and 110

- 3, into engagement with friction member 35 thereby transmitting rotary motion from shaft 24 to pinion 25 and thence to drum gear 31.
- 5 Cam 45 is similarly oscillated from lever 52, fixed to tubular shaft 53 about shaft 49, through arm 56 fixed to said tubular shaft and connected by links 57, 57 with cam arm 47. By this arrangement, controlled by 10 levers 48, 52, drums 2 and 4 may be rotated one at a time from motor 11, or simultaneously and at varying speeds as desired, governed by the amount of friction applied to said friction members.
- 15 The lowering action resulting from the pull of the cables in unwinding from drums 2, 4, is governed by foot levers 58, 59, respectively. Said levers turn freely on shaft 60 fixed in bracket 61 secured to upright 6.
- 20 Lever 59 is connected by links 62, 62 with the free end of arm 63 fixed to rock shaft 64. Said rock shaft has bearings in frame 21 and brackets 54, 55. Dished friction member 35 has wrapped about its periphery 25 band brake 65 connected in the usual manner at one end with cross member 9 fixed to uprights 5 and 6, and the other end to arm 67 fixed to rock shaft 64. Dished friction member 36 has band brake 68 wrapped 30 thereabout. One end of said band brake is fixed to cross member 9 and the other end to arm 69 fixed to tubular shaft 70 about rock shaft 64. Another arm 71 fixed to tubular shaft 70 is connected by links 72, 72 with 35 foot lever 58. By depressing the left hand end of lever 59, Fig. 1, band brake 65 is caused to grip member 35 and retard its rotation. Lever 58 similarly depressed will cause band brake 68 to grip member 36 and 40 similarly retard its rotation. Said band brakes may be operated independently, one at a time, or simultaneously and to such extent of result as desired.
- 45 There is thus provided a hoisting mechanism driven from one motor and controlled for various speeds of hoisting and lowering by means of four levers, all operable by one man.
- 50 I claim:
- 55 1. In a hoisting mechanism the combination of a control-shaft, opposite pinions mounted for free rotation on said shaft, an infacing friction member carried by each pinion, opposite friction members slidably mounted on said shaft for engagement with
- 55 said pinion friction members respectively, said slidable friction members being constrained for rotation with said shaft, a fixed double faced cam about said shaft between said slidable friction members, a cam mounted for oscillation on said shaft and for engagement with said fixed cam between each of said slidable friction members and said fixed cam, a rock shaft having a lever fixed thereto, means operably connecting said rock shaft and one of said oscillatable cams, a tubular rock shaft about said rock shaft and having a lever fixed thereto, means operably connecting said tubular rock shaft with the other oscillatable cam, said levers being 60 operable simultaneously or independently at will, a motor mounted on said mechanism, and means for rotating said control-shaft at either of a plurality of speeds from said motor.
- 65 2. In a hoisting mechanism the combination of a control-shaft, opposite pinions mounted for free rotation on said shaft, a friction member carried by each pinion, opposite friction members slidably mounted on 70 said shaft for engagement with said pinion friction members respectively, said slidable friction members being constrained for rotation with said shaft, a fixed double faced cam contiguous to said shaft between said slidable friction members, a cam mounted for oscillation on said shaft and for engagement with said fixed cam between each of said slidable members and said fixed cam, a rock shaft having a lever fixed thereto, means operably connecting said rock shaft and one of said oscillatable cams, a tubular rock shaft about said rock shaft and having a lever fixed thereto, means operably connecting said tubular rock shaft with the other oscillatable cam, a brake operably connected with each of said pinions, a second rock shaft having a lever fixed thereto, means operably connecting said rock shaft and one of said brakes, a tubular rock shaft about said second rock shaft and having a lever fixed thereto, and means operably connecting said second tubular rock shaft with the other of said brakes, said levers being 80 operable simultaneously or independently at will for oscillating said rock shafts.
- 85 3. In a hoisting mechanism the combination of a control-shaft, opposite pinions mounted for free rotation on said shaft, an infacing friction member carried by each pinion, opposite friction members slidably mounted on said shaft for engagement with
- 90 4. In a hoisting mechanism the combination of a control-shaft, opposite pinions mounted for free rotation on said shaft, an infacing friction member carried by each pinion, opposite friction members slidably mounted on said shaft for engagement with
- 95 5. In a hoisting mechanism the combination of a control-shaft, opposite pinions mounted for free rotation on said shaft, an infacing friction member carried by each pinion, opposite friction members slidably mounted on said shaft for engagement with
- 100 6. In a hoisting mechanism the combination of a control-shaft, opposite pinions mounted for free rotation on said shaft, an infacing friction member carried by each pinion, opposite friction members slidably mounted on said shaft for engagement with
- 105 7. In a hoisting mechanism the combination of a control-shaft, opposite pinions mounted for free rotation on said shaft, an infacing friction member carried by each pinion, opposite friction members slidably mounted on said shaft for engagement with

In witness whereof, I hereby affix my signature this 1st day of November, 1923.

JOHN T. HORTON.
